US00D889959S

(12) **United States Design Patent** (10) **Patent No.:** **US D889,959 S**
Burke et al. (45) **Date of Patent:** **** Jul. 14, 2020**

(54) **PACKAGE**(71) Applicant: **Medline Industries, Inc.**, Northfield, IL (US)(72) Inventors: **Damian Burke**, Lake Zurich, IL (US); **Mark Vanderhulst**, Chicago, IL (US); **Emily Somers**, Cary, IL (US)(73) Assignee: **Medline Industries, Inc.**, Northfield, IL (US)(**) Term: **15 Years**(21) Appl. No.: **29/650,859**(22) Filed: **Jun. 11, 2018****Related U.S. Application Data**

(63) Continuation of application No. 29/577,636, filed on Sep. 14, 2016, now Pat. No. Des. 820,675.

(51) **LOC (12) Cl.** **09-03**(52) **U.S. Cl.**USPC ..... **D9/432**(58) **Field of Classification Search**

CLAIM

The ornamental design for a package, as shown and described.

DESCRIPTION

FIG. 1 is a perspective view of a package in accordance with a first embodiment of our new design;
FIG. 2 is a top plan view of the package of FIG. 1;
FIG. 3 is a bottom plan view of the package of FIG. 1;
FIG. 4 is a front elevation view of the package of FIG. 1, the rear elevation view being identical thereto;
FIG. 5 is a side elevation view of the package of FIG. 1, the other side elevation view being identical thereto;
FIG. 6 is a perspective view of a package in accordance with a second embodiment of our new design;
FIG. 7 is a top plan view of the package of FIG. 6;
FIG. 8 is a bottom plan view of the package of FIG. 6;
FIG. 9 is a front elevation view of the package of FIG. 6, the rear elevation view being identical thereto;
FIG. 10 is a side elevation view of the package of FIG. 6, the other side elevation view being identical thereto;

FIG. 11 is a perspective view of a package in accordance with a third embodiment of our new design;

FIG. 12 is a top plan view of the package of FIG. 11;
FIG. 13 is a bottom plan view of the package of FIG. 11;
FIG. 14 is a front elevation view of the package of FIG. 11, the rear elevation view being identical thereto;

FIG. 15 is a side elevation view of the package of FIG. 11, the other side elevation view being identical thereto;
FIG. 16 is a perspective view of a package in accordance with a fourth embodiment of our new design;

FIG. 17 is a top plan view of the package of FIG. 16;
FIG. 18 is a bottom plan view of the package of FIG. 16;
FIG. 19 is a front elevation view of the package of FIG. 16, the rear elevation view being identical thereto; and,

FIG. 20 is a side elevation view of the package of FIG. 16, the other side elevation view being identical thereto.
The smaller, lighter dashed lines in the shape of an ellipse in FIGS. 1, 2, 6, 7, 11, 12, 16, and 17 depict perforations and are part of the claimed design. The longer, darker dashed lines in the shape of letter "S" (FIGS. 1, 2, 6, 7, 11, 12, 16, and 17) and in the shape of the bottom and side surfaces of the package depict portions of the package that form no part of the claimed design.

The surface stippling in FIGS. 1, 2, 6, 7, 11, 12, 16, and 17 represents a contrast in appearance relative to non-stippled areas.
